PAPER CUTTING KNIFE OR THE LIKE

Donald W. Doman, Janesville, Wis., assignor to The Parker Pen Company, Janesville, Wis., a corporation of Wisconsin

Filed Mar. 7, 1962, Ser. No. 69,120

Term of patent 14 years

(Cl. D22—3)

FIG. 1

FIG. 2

FIG. 3

FIG. 4

FIG. 5

FIG. 6

FIG. 7

FIG. 1 is a side elevational view of a paper cutting knife or the like showing my new design;

FIG. 2 is a top plan view of the device of FIG. 1;

FIG. 3 is a bottom plan view of the device of FIG. 1;

FIG. 4 is a front end view thereof looking in the direction of the arrows 4—4 of FIG. 1;

FIG. 5 is a rear end view thereof looking in the direction of the arrows 5—5 of FIG. 1;

FIG. 6 is a fragmentary sectional view taken on line 6-6 of FIG. 1; and

FIG. 7 is a fragmentary sectional view taken on line 7-7 of FIG. 2.

The essential features of my design reside in the portions shown in solid lines on the drawing.

I claim:

The ornamental design for a paper cutting knife or the like, as shown and described.
